UNITED STATES PATENT OFFICE.

WILLIAM T. BARRATT, OF BENNINGTON, VERMONT, ASSIGNOR TO CHARLES COOPER, OF BENNINGTON, VERMONT.

ADJUSTABLE CAM FOR CIRCULAR-KNITTING MACHINES.

SPECIFICATION forming part of Letters Patent No. 777,063, dated December 13, 1904.

Application filed February 23, 1904. Serial No. 194,640. (No model.)

To all whom it may concern:

Be it known that I, WILLIAM T. BARRATT, a citizen of the United States, residing at Bennington, in the county of Bennington and State 5 of Vermont, have invented new and useful Improvements in Adjustable Cams for Circular-Knitting Machines, of which the following is a specification.

This invention relates to an improved cam 10 for circular-knitting machines, the object of the invention being to provide a cam which can be adjusted so as to regulate the throw or distance to which the needles in said machine may be raised or lowered and which can be 15 adjusted quickly and with precision when the different parts of the machine are assembled without inconvenience and without interfering with any of said parts.

The invention consists in the combination 20 and arrangement of parts set forth in the following specification, and particularly pointed out in the claims thereof.

Referring to the drawings, Figure 1 is a front elevation of my improved cam. Fig. 2 25 is a rear elevation of the same. Fig. 3 is a section taken on line 3 3 of Fig. 1, illustrating in addition to said cam a portion of a needle-cylinder of a circular-knitting machine. Fig. 4 is a detail section taken on line 4 4 of 30 Fig. 1. Fig. 5 is a detail front elevation of the cam-adjusting lever. Fig. 6 is a detail front and side elevation of the arm by means of which said lever is rocked upon its pivot.

Like numerals refer to like parts throughout the several views of the drawings.

In the drawings, 10 is the lower bed of a circular-knitting machine; 11, the lower cylinder of said machine; 12, a lower cylinder-needle, and 13 the lower rotary ring, to which 40 the lower cylinder 11 is fastened, said ring and cylinder having a rotary motion imparted thereto by a gear 14, fast to said ring 13, and driven by a pinion (not shown) in a manner well known to those skilled in this art.

45 My improved adjustable cam comprises a bracket 15, rigidly fastened to the lower bed 10 by means of screws 16. Said bracket has a vertically-extending flange 17 integral there-

with, and upon the inner face of said flange adjacent to the needle-cylinder 11 are formed 50 ways 18. A slide 19 is adapted to be moved up and down in said ways and has fastened to the inner face thereof an inclined cam-plate 20, adapted to engage the jacks 21 of the lower cylinder - needles 12 and move them downwardly in the tracks of said cylinder. The slide 19 is moved upwardly or downwardly by means of a lever 22, pivoted upon a screw 23, fast to the flange 17 and engaging a clamp-screw 24, which projects through an elongated 60 slot 25 in said lever and also through a slot 26, formed in the flange 17 and into the slide 19, with which said clamp-screw 24 has screw-threaded engagement.

An arm 27 is pivoted to rock upon the flange 65 17 by a shank 28, integral therewith and having screw-threaded engagement with said flange. The arm 27 projects into and through an orifice or slot 29, formed in the lever 22, and has a screw-driver slot 30 formed therein, by 70 means of which it may be rocked upon its pivot. The slot 29 is substantially triangular in shape, the end 29' being of greater width than the end 29" of said slot, the arm 27 being pivoted in the wider end 29' of said slot 75 to allow the lever 22 to be rocked upon its pivot 23.

To adjust the cam-plate 20 upwardly or downwardly, the clamp-screw 24 is loosened and the arm 27 is rotated toward the right or left 80 by means of a screw-driver, raising or lowering, respectively, the lever 22 and through the screw 24 the slide 19, with the cam-plate 20 attached thereto. After the cam-plate has been moved as much as may be desired up or 85 down said cam-plate 20, slide 19, and lever 22 are clamped to the vertical flange 17 by tightening the clamp-screw 24. The cam-plate 20 is in the present instance a cam-plate for drawing down the needles of the lower 90 cylinder; but it is evident that the same device may be utilized for raising and lowering cam-plates of various shapes and inclinations without departing from the spirit of my invention.

95 The advantage secured from my adjustable

cam is that by the use of a screw-driver the cam-plate may be raised or lowered to a very slight extent and conveniently reached for such adjustment without interfering with any 5 of the other devices—such as presser-stands, brackets, and the like—which are assembled around the needle-cylinders of a circular-knitting machine in a manner well known to those skilled in this art.

10 Having thus described my invention, what I claim, and desire by Letters Patent to secure, is—

15 1. An adjustable cam for knitting-machines comprising a bracket, ways formed in said bracket, a slide adapted to be moved in said ways, a cam-plate fast to said slide, a screw having screw-threaded engagement with said slide, a lever pivoted to said bracket and engaging said screw, and means to positively 20 rock said lever in opposite directions and raise and lower said screw and cam-plate.

25 2. An adjustable cam for knitting-machines comprising a bracket, ways formed in said bracket, a slide adapted to be moved in said ways, a cam-plate fast to said slide, a screw having screw-threaded engagement with said slide, a lever provided with a slot and pivoted to said bracket and engaging said screw, means to positively rock said lever in opposite 30 directions and raise and lower said screw and cam-plate, consisting of an arm pivoted to said bracket and projecting into said slot provided in said lever, whereby said lever may be positively rocked in opposite directions upon its pivot and said slide and cam-plate positively raised and lowered. 35

40 3. An adjustable cam for knitting-machines comprising a bracket having a vertically-projecting flange thereon, a cam-plate fast to the inner face of said flange, a lever provided with a slot and pivoted to the outer face of said flange and connected to said cam-plate, and an arm pivoted to said flange and projecting into said slot provided in said lever, where- 45 by said lever may be positively rocked in op-

posite directions upon its pivot and said slide and cam-plate positively raised and lowered.

4. An adjustable cam for knitting-machines comprising a bracket, ways formed in said bracket, a slide adapted to be moved in said ways, a cam-plate fast to said slide, a screw having screw-threaded engagement with said slide, a lever provided with a slot and pivoted to said bracket and engaging said screw, means to positively rock said lever in opposite directions and raise and lower said screw and cam-plate, consisting of an arm pivoted to said bracket and projecting into said slot provided in said lever, whereby said lever may be positively rocked in opposite directions upon its pivot and said slide and cam-plate positively raised and lowered, said slot being of different widths at the opposite ends thereof, respectively. 55

5. An adjustable cam for knitting-machines comprising a bracket, ways formed in said bracket, a slide adapted to be moved in said ways, a cam-plate fast to said slide, a screw having screw-threaded engagement with said slide, a lever provided with a slot and pivoted to said bracket and engaging said screw, means to positively rock said lever in opposite directions and raise and lower said screw and cam-plate, consisting of an arm pivoted to said bracket and projecting into said slot provided in said lever, whereby said lever may be positively rocked in opposite directions upon its pivot and said slide and cam-plate positively raised and lowered, said slot being of different widths at the opposite ends thereof, respectively, the pivoted end of said arm located in the wider end of said slot. 75

In testimony whereof I have hereunto set my hand in presence of two subscribing witnesses.

WILLIAM T. BARRATT.
